UNITED STATES PATENT OFFICE

HENRI LENTULO, OF PARIS, FRANCE

PLUGGING TOOL

Application filed February 16, 1928, Serial No. 254,787, and in France February 25, 1927.

The present invention relates to tools or instruments for the plugging or tamping of pastes, cements or other stopping material into dental hollows and other narrow-mouthed cavities of all kinds.

It is particularly applicable to the plugging or tamping of antiseptic pastes into the root channels of teeth, void of their organic content, in order to produce the complete filling of the cavity.

This operation is carried out by the introduction of the tool or instrument into the interior of the channel or of the space to be filled, the plugging tool being covered with ¹⁵ pasty or semi-liquid material which as a result of a rapid rotary movement imparted to the instrument is driven, pushed, and projected into the empty spaces, which are thus filled up.

²⁰ The invention consists in a rotary paste plugging or tamping device for the introduction of plastic substances into narrow-mouthed cavities of all kinds, in particular into the dental cavities, the tool or instrument being constituted by a wire of suitable dimensions, wound into a helix and mounted upon the extremity of a shank or mandrel allowing of imparting to it a rapid rotary movement. The plugging tool is preferably ²⁵ constructed with the actual tamping device in the form of a metal wire of round or angular cross section, wound in a helix of uniform or variable pitch around an imaginary or a concrete core wholly or in part, this core ³⁰ having the shape of a cone, rat-tail or other.

The invention also comprises means for connecting the helically coiled wire with the shank or mandrel which serves as its support, and rendering these parts solid or integral ⁴⁰ with one another.

Upon the accompanying drawings, to which reference will be made in the subsequent description, Figures 1 and 6 represent ⁴⁵ on an enlarged scale a plugging tool constructed in accordance with the invention.

Figures 2, 3 and 4, likewise represent on the same enlarged scale, various modes of attachment of the wire terminating the plugging tool to its support.

Figure 5 is a transverse section taken along the line $x-x$ of Figure 2.

The instrument comprises essentially a thin metal wire f , of rounded or angular cross section, and of a diameter varying according to the needs of the case; in the most frequent instances relating to the filling of dental hollows, the diameter will be approximately some hundredths of a millimetre. This wire f is wound in a helix f^2 , of uniform or varying pitch as required, around an imaginary core for a length which may vary for example from 1 centimetre upwards, according to the length or depth of the channel or space to be filled with the paste.

The diameter of the core around which the wire f is wound may also be varied as desired; it will have for example a diameter slightly greater than twice the diameter employed for the wire f .

This same imaginary core is not necessarily or constantly cylindrical; it may assume various shapes, for example a drawn-out conical shape, like a rat-tail, the widest part corresponding to the base of the instrument.

At the base of the working part of the plugging tool, the metal wire f is connected to a shank or mandrel M , intended to transmit to it the rotary drive which it in turn receives from a dental engine or other motor.

The fixing of the wire f upon the shank M may be carried out in widely varying manners.

Figures 2, 3 and 4 of the drawing represent by way of example three modes of fixing ⁸⁵ the wire f upon its supporting shank or mandrel M .

Figure 2 shows a method of attachment in the shape of a figure 8.

Towards the end where the shank M is to receive the wire f there are provided two grooves 3 and 4 on opposite sides. At the bottom of the grooves 3 and 4, two holes 5 and 6 are drilled at a certain distance apart, through which there passes one end of the metal wire f .

This wire extends down the upper part of the groove 4, is threaded into the upper hole 6, and upon leaving the latter enters the lower part of the groove 3; after passing down ¹⁰⁰

this groove, towards the lower hole 5, which it passes through, it encounters the opposite groove 4, rises again along the lower part of the latter, re-enters the first hole 6 and is again engaged therein from the same side as at the start; on leaving, it rises and extends along the upper part of the groove 3 which reaches to the top of the shank; it then again encounters the other extremity 10 f^1 , turned up stiffly and straight in prolongation of the top of the shank, and is coiled in a helix f^2 , first around a small portion of this wire f^1 , which forms a prolongation of the end of the shank, then extends beyond it and 15 is wound around the imaginary core as has been stated previously, so as to form the more active working portion of the plugging tool.

As shown in Figure 6, the extremity f^1 of the wire f may be of greater or less length 20 and may constitute the whole or a part of the core, which in this case is no longer an imaginary core as contemplated above but an actual concrete core, extending for the whole length of the helix f^2 or for only a part of 25 that length.

Naturally the helically wound wire may be in contact wholly or in part with the concrete core, or again it will be permissible to provide a certain clearance between these 30 elements.

In the example of Figure 3, the basal extremity of the helicoidal wire f may be screwed directly into the end of the shank or mandrel M , or may be maintained in the 35 upper extremity of the said shank or mandrel by clamping, adhesion, wedging, etc.

In the example of Figure 4, the instrument is constructed in a single piece, the helicoidal wire f being constituted by the drawing out 40 of the end of the shank M .

Naturally all suitable materials may be utilized for the manufacture either of the wire f or the shank or mandrel M .

As above stated, the drawings show the 45 instrument on an enlarged scale and the wire f is of a diameter equal to only some hundredths of a millimetre. The paste or plastic stopping material which is supplied to the helix or coil f^2 is preferably of the consistency of vaseline. This paste is fed forward by the rotating coil f^2 on the principle 50 of the inclined plane or helix until such paste has reached the end of the wire f which has been pushed to the end or bottom of the 55 canal. Owing to the thinness of the wire and of the coil f^2 , the device can easily follow the path or bore of a non-rectilinear canal in the root of the tooth, and the construction and flexibility of the device will allow air 60 to escape from the canal.

What I claim is:—

1. A dental plugging tool, consisting of a rotatable device, said device including a wire coiled around the rotary axis of the device 65 adjacent to the working point of the tool

and adapted to enter at least partly into the cavity to be plugged.

2. A dental plugging tool, comprising a support member and a coiled wire member adapted to receive plugging material, said members being fixed together and rotatable about a common axis, said coiled wire member when rotated acting to propel plugging material into the cavity to be plugged. 70

3. A rotary dental plugging tool, comprising a shank and a point section, said point section including a tapering coil of wire wound around an axis in prolongation of the axis of said shank, and adapted to enter at least partly into the cavity to be plugged. 75

4. A rotary dental plugging tool, comprising a shank and a flexible point section, said point section including a helical coil of very fine wire and being secured to said shank with its helical axis in prolongation of the axis of said shank. 80

5. A rotary plugging tool, comprising a shank, said shank being apertured transversely of its axis, and a point section, said point section including a coil of wire, one end of said coil being secured to said shank by passing through said apertured shank, said coil being coaxial with said shank. 85

6. A rotary plugging tool, comprising a shank, said shank having apertures transverse to its axis, and a point section, said point section including a tapering helical coil of wire, the larger end of said coil being secured to said shank by passing the wire through said apertures, and the extremity of said wire being disposed in the common axis of said coil and said shank. 90

7. A rotary plugging tool, comprising a shank, said shank having longitudinal grooves on opposite sides adjacent to one end thereof and having transverse apertures extending between said grooves, and a point section, said point section including a tapering helical coil of wire, the larger end of said coil being secured to said shank by passing the wire along said grooves and through said apertures, and the extremity of said wire being disposed in the common axis of said coil and said shank. 105

8. A rotary plugging tool, comprising a shank and a point section, said point section including a coil of wire wound about a core surface having its axis in prolongation of the axis of said shank. 110

9. A rotary plugging tool, comprising a shank and a point section, said point section including a helical coil of wire, said helical coil forming an envelope to a core of diameter not less than that of the wire composing said coil. 115

10. In a dental instrument, the combination with a point section of fine wire, of a paste-propelling coil member also of fine wire and integral with said point section, said point section and coil member being 120

adapted to enter into a tooth canal, means for imparting rotary movement to said propelling coil and point section, and means for holding and controlling said point section and coil member during their rotary movement.

11. As a new dental instrument, a point section, a supporting member integral with said point section, said supporting member including a helical coil acting on the inclined plane principle, said point section and supporting member both being of very fine wire adapted to enter a dental canal, and means for rotating said point section and supporting member while at least a portion of said coil is within the dental canal.

12. A dental tool for feeding forward pasty stopping materials, comprising a flexible point section adapted to be inserted to the end of a root canal, a member integral with said point section and acting as a support therefor, said supporting member including a helical coil adapted to act on the inclined plane principle, said point section and coil being of fine wire, flexible and insertible into the root canal, and means for imparting rotary movement to said coil and point section whereby the coil will cooperate with the walls of the canal to feed forward the pasty materials.

In testimony whereof I hereunto affix my signature.

HENRI LENTULO.
